ERNEST H. BENNETT, OF EAST ORANGE, NEW JERSEY, ASSIGNOR TO JOHN H. BROMLEY AND EDWARD BROMLEY, COPARTNERS, TRADING AS JOHN BROMLEY AND SONS, OF PHILADELPHIA, PENNSYLVANIA.

DESIGN FOR A RUG.

No. 38,796.

Specification for Design.

Patented Sept. 10, 1907.

Application filed July 27, 1907. Serial No. 385,928. Term of patent 3½ years.

To all whom it may concern:

Be it known that I, ERNEST H. BENNETT, a citizen of the United States, residing in East Orange, county of Essex, State of New Jersey, have invented a certain new original Design for a Rug, of which the following is a specification, reference being had to the accompanying drawings, forming a part thereof.

My design relates to and is intended for the surface ornamentation of a woven rug.

In said drawings, is shown a plan view of one-half thereof, the other half of the design (not shown) being a duplicate or repeat thereof.

I claim:—

The ornamental design for a rug, as shown.

ERNEST H. BENNETT.
